UNITED STATES PATENT OFFICE.

PATRICK B. DELANY, OF SOUTH ORANGE, NEW JERSEY, ASSIGNOR TO SECRET
TELEGRAPH COMPANY, OF NEW YORK, N. Y., A CORPORATION OF DELAWARE.

TELEGRAPHY.

1,244,477.

Specification of Letters Patent. Patented Oct. 30, 1917.

Application filed December 27, 1916. Serial No. 139,103.

To all whom it may concern:

Be it known that I, PATRICK B. DELANY, a citizen of the United States, residing at South Orange, in the county of Essex and 5 State of New Jersey, have invented certain new and useful Improvements in Telegraphy, of which the following is a specification.

This invention relates broadly to the art 10 of telegraphy, and more particularly to a method of receiving the signals or messages transmitted.

The principal object of the present invention is to provide a safeguarding sounder 15 for use in connection with the main sounder ordinarily employed and so positioned in hearing relation to the general public that the signals recorded thereby predominate in 20 loudness over the signals recorded by the main sounder.

A further object of my invention is to provide a safeguarding sounder of the nature referred to which shall record reversals of the signals recorded by the main receiving instruments.

In the accompanying drawings, Figure 1 is a diagrammatic view illustrating one form of my invention.

Fig. 2 is a diagrammatic view of a slightly 30 modified form thereof.

Fig. 3 is a diagrammatic view of a further modification.

Fig. 4 is a diagrammatic view of a mechanically operated sounder.

Fig. 5 is a perspective view showing a 35 possible arrangement of instruments.

With systems now in use for receiving telegraphic messages within hearing of the general public, such as in branch offices of 40 hotels, office buildings and the like, it is comparatively easy for an outsider who has a knowledge of telegraphy to get within hearing distance of the receiving instruments and read the message being transmitted 45 or received at such office. While the disadvantages of such publicity have long been recognized, it has, so far as I know, never been remedied except by installing the instruments in a separate room. It often 50 happens that due to the limited space provided it is almost impossible to set aside such a room. It is the purpose of the present invention to overcome these objections to systems ordinarily employed, and to 55 eliminate to a large extent the leakage of

supposedly private messages. This is accomplished by providing what may be termed a supplemental or safeguarding sounder for use in connection with the main receiving sounders or instruments now in 60 use, and placed within hearing distance of the public, and controlling the operation thereof either from such instruments, or by independent mechanically operated devices. This may be successfully done by causing 65 the vibrating member of the safeguarding sounder to record signals conflicting with the signals received by the main instruments.

Referring now more particularly to Fig. 70 1 of the drawings, I have shown a relay R in circuit with the line wires L and adapted to control the operation of the main receiving instrument or sounder S in the usual manner. With the main line circuit open, 75 which is the condition which exists just prior to the transmitting of a message, the armature 1 of the relay will be drawn by the spring 2 into what is normally its inoperative position, which position is indicated in full lines in the drawing. In the present system advantage is taken of this position for controlling the actuation of the supplemental or safeguarding sounder SS in the manner hereinafter described. Upon 80 85 the closing of the sending key, the relay will be energized thereby attracting its armature, against the action of the retaining spring, into electrical contact with the point 4. This will in turn close the local circuit 90 of the sounder S from the point 4, through the wire 5 to the sounder, and thence from the wire 6 and battery B to the relay armature through the wire 7. This causes the armature 21 of the sounder to be attracted 95 in the usual manner for recording the signal transmitted. Upon the opening of the sending key, the relay armature will again resume the full line position, thereby closing the circuit through contact 8, wire 9 and 100 switch 10 to the safeguarding sounder, the opposite side of the circuit being completed through the wire 11 and battery B as before described. It will thus be seen that upon its back stroke the relay armature 105 closes the local circuit of the safeguarding sounder thereby causing the same to give reversals of the signals received by the main line sounder, the circuit of which is closed on the ordinary front stroke of the relay. 110

By providing a switch 10, one safeguarding sounder may be used in connection with several different relays, one of which is indicated at R' connected in the line L'. By 5 moving the switch arm from its full position *a* to its dotted line position *b*, the circuit of the safeguarding sounder SS which was formerly closed by the back stroke of the relay armature 1, will now be opened, 10 when the armature 1' is in attracted position. The relay armature 1', which operates in a manner similar to that of armature 1, will when attracted close the local circuit of the sounder S through contact 15 12, wire 14 to the wire 5 thence through the battery and wire 15 to the armature 1'. When the sending key is in open position, the spring 2' will attract the armature into its full line position, thereby causing the 20 circuit through the safeguarding sounder to be closed through the contact 16 and switch 10, the return circuit being through the battery and wire 15 to the armature. The operation of the relays R and R' is the 25 same, the switch 10 making it possible to use either one at will in connection with the safeguarding sounder.

In some instances it may be desirable to control the safeguarding sounder by the 30 operation of the armature of the receiving instrument. If such is the case, the switch 19 is moved to its dotted line position and the switch 10 is moved to its neutral position. The relays operating in the manner 35 heretofore described to actuate the sounder, the back stroke of its armature 21 will now close the circuit of the safeguarding sounder through the contact 17, wire 18, switch 19, and wire 20, the return circuit 40 being completed through wire 11, battery B, wire 22 to the sounder armature.

In any of the circuits heretofore described the safeguarding sounder is operated upon the back stroke of one of the instruments 45 now in use, so that it must produce a reversal of the signal received by such instrument. In order that the signal given thereby may predominate in loudness over the signal received by the main sounder, the 50 safeguarding sounder may be placed in a window or adjacent a partition W which is within hearing distance of the general public, or, as shown in Fig. 5, it may be positioned at any desirable point on the counter 55 provided for public use.

If desired, the armature of the safeguarding sounder may be operated in unison with the operation of the armature of the main sounder, and the confusion to the public 60 accomplished by muffling the stroke of the safeguarding armature in one direction. The circuit for such a system is illustrated in Fig. 2, and comprises, in addition to the connections already described, a wire 9', 65 connected to the contact 4 and to the switch

10, the effect of which is to connect both of the sounders in parallel and insuring their operation in unison. The lower anvil 23 of the safeguarding sounder is in this instance provided with a buffer or button of 70 resilient material which prevents the armature 24 from making any sound on its front stroke, but permits it to give the customary sound on its back stroke. It is well known that the back strokes of a receiving instrument are comparatively difficult to read, so that the desired confusion to the public may be obtained in this manner. 75

In Fig. 3 there is illustrated diagrammatically a slight modification of the circuit shown in Fig. 1. In this figure separate local circuits are provided for each of the relays and sounder, the relay R² operating to control the actuation of sounder S², and the relay R³ to control the sounder S³. 80 The safeguarding sounder SS' may be operated by the armatures of either the relay or sounders as shown in Fig. 1, but by way of example I have shown the same as being controlled by the sounder armatures. The back stops or contacts of each of the sounders are connected by the wire 25, while the armatures themselves are connected to the switch points *a'* and *b'* by the wires 26 and 27 respectively. One side of the circuit of 85 the safeguarding sounder SS' is electrically connected with the wire 25 through wire 28, the circuit being completed through the sounder winding, the wire 29, and battery to the switch 10' adapted to operate the safeguarding sounder from either of the points *a'* or *b'* depending upon which of the relays 90 is in use.

At times it may be desirable to create a 95 disturbing or interfering noise independently of the operation of either the relay or sounder. This may be conveniently accomplished by the mechanism shown in Fig. 4. As illustrated, this comprises a mechanically operated tape T controlling the operation of the sounder S*, the circuit being 100 made and broken by the brush working in the perforation in the tape in any well known manner. This will constantly produce conflicting or interfering signals for 105 successfully carrying out my invention. 110

By way of concrete example of the usefulness of one form of my device in operation, let it be supposed that it is desired to transmit the letter A consisting of a dot and 115 dash. This signal will be recorded by the main sounder in its regular order, but will be recorded by the safeguarding sounder as a dash followed by a dot which represents the letter N. The letter N being the signal 120 heard by an outsider, while the letter A is the signal transmitted, it will be apparent that my invention successfully accomplishes its purpose and protects the secrecy of telegraphic communications. 125

While I have illustrated the preferred manner of carrying out the foregoing objects, it will be apparent that changes may be made in circuits and connections illustrated without departing from the spirit of the invention and scope of the appended claims.

What I claim is:—

1. A system for protecting the secrecy of telegraphic messages, comprising a receiving sounder, a safeguarding sounder, and means for causing said safeguarding sounder to give telegraphic reversals of the signals received by the receiving sounder.

15 2. A system for the protection of telegraphic messages, comprising receiving instruments including a relay and a telegraphic sounder controlled thereby, and a safeguarding telegraphic sounder controlled by one of said receiving instruments.

20 3. A system for protecting telegraphic messages, comprising receiving instruments including a telegraphic sounder, and a relay having an armature controlling the operation of said sounder upon movement in one direction, a safeguarding telegraphic sounder, and means for operating said safeguarding sounder upon movement of the relay armature in the other direction.

4. A system for protecting the secrecy of 30 a telegraphic message, comprising a receiving station, a private operator's sounder at said station, and a public safeguarding sounder, both of said sounders being adapted to produce telegraphic signals throughout the time said message is being received.

5. The method of protecting the secrecy of a telegraphic message which consists in producing a series of signals similar in nature to but constituting reversals of the signals comprising said message.

6. The method of protecting the secrecy of a telegraphic message which consists in producing a series of signals similar in nature to but constituting reversals of the signals comprising said message, said reversals being produced with predominating loudness within the hearing of a bystander.

7. The method of protecting the secrecy of a telegraphic message which consists in 50 producing a series of signals similar in nature to but interfering in sound with the signals comprising said message to confuse a bystander attempting to read the same.

In testimony whereof, I have hereunto 55 subscribed my name.

PATRICK B. DELANY.
